Attys.

UNITED STATES PATENT OFFICE.

CHARLES EDWARD FRANCIS, OF HOLLOWAY, LONDON, ENGLAND, ASSIGNOR TO
VICKERS LIMITED, OF WESTMINSTER, ENGLAND.

SEWING-MACHINE.

1,241,949.

Specification of Letters Patent.

Patented Oct. 2, 1917.

Application filed April 18, 1917. Serial No. 162,866.

To all whom it may concern:

Be it known that I, CHARLES EDWARD FRANCIS, a subject of the King of Great Britain, residing at 3 Crayford road, Holloway, in the county of London, England, have invented certain new and useful Improvements in Sewing-Machines, of which the following is a specification.

This invention relates to lock stitch sewing machines of the kind in which there is employed a rotary hook or looptaker with a non-rotary bobbin case within it in which the bobbin for the bobbin thread is arranged, and the main object of the said 10 invention is to provide stitch forming means that shall be suitable in design for work of practically all characters from the lightest material and finest thread to the heaviest material and coarsest thread usually dealt 15 with in machines of the kind referred to and also such that in the same machine a wider range of work may be performed than heretofore in machines of the said kind. In other words the main object of the present 20 invention is to combine the respective advantages in known machines of the said kind wherein the rotary hook makes one revolution for each stitch and those in which the said hook makes two revolutions for each 25 stitch and those in which the said hook makes three revolutions for each stitch and so to provide a stitch forming mechanism which as a type is equally well suited for use in a domestic sewing machine or in a 30 sewing machine for factory use and for operating on light or heavy fabrics, leather or the like and which also will enable the same individual machine to operate on a larger range of character of work than here- 35 tofore.

According to the said invention the outer part of the bobbin case and the inner side of a ring holder employed for retaining the bobbin case in the rotary hook or looptaker 40 have corresponding contacting surfaces gradually varying in contour in the direction of rotation of the looptaker, to counteract the tendency of the bobbin case to rotate and rise while permitting proper passage of 45 the loop. The bobbin case has a peripheral bearing in the looptaker toward the inner side thereof and the bobbin case also has a radial projection or lug directly in front of

a needle aperture in the said case the said lug having an eye through which the bobbin 55 thread is led upwardly to the needle hole in the throat plate out of the path of the looptaker, the inner face of the said lug being adapted to assist in forming the loop to be engaged by the looptaker. The bob- 60 bin thread may pass over the outer face of the said lug and the tension on the said thread may conveniently be obtained by a tension spring on the outer part of the bob- 65 bin case bearing on the thread as it passes over the outer face of the said lug. In con- 70 sequence of the construction described the needle aperture in the bobbin case may be so situated that the needle descends therein in a plane outside the bobbin so that the latter cannot be injured by the needle if imperfectly secured.

The said invention is hereinafter more particularly described with reference to the accompanying drawings which illustrate the 75 preferred embodiment thereof.

The invention is illustrated in the accom- 80 panying drawings, in which:—

Figure 1 of the said drawings is an end elevation of part of the head of a sewing machine showing the relative positions of the needle and the hook when the hook point is entering the loop formed by the needle thread.

Fig. 2 is a plan view of the hook in the 85 position shown in Fig. 1, the needle being shown in section.

Fig. 3 shows sectional views of the hook on the line X—X of Fig. 1 the bridge piece hereinafter referred to being omitted. 90

Figs. 4 and 5 show the bridge piece in side elevation and plan view respectively.

Figs. 6 and 7 show the bobbin in end elevation and side view respectively.

Fig. 8 shows the bobbin case in elevation 95 from the back, *i. e.*, the open end;

Fig. 9 is a side elevation of same;

Fig. 10 is a section on line Y—Y of Fig. 8, looking toward the right; and

Fig. 11 is a front view of the bobbin case, 100 Fig. 8.

Figs. 12 and 13 are side and front eleva- 105 tions respectively of the bobbin-case tension spring (not shown in Figs. 8–11).

Fig. 14 is a plan view of Fig. 8 with the 105 bobbin-case tension spring in position.

Fig. 15 is an inner end elevation of the bobbin-case holding ring.

Fig. 16 is a side elevation of same.

Referring to the drawings:

5 The hook or looptaker rotates once only for each stitch and is a cup-shaped body A rigidly mounted on a rotatable shaft B—to which variable motion is imparted—and having an outwardly inclined loop-taking 10 point a formed on its rim. The edge or face of the said rim lies in one plane for rather more than half the periphery, the remainder being set back, as shown at a' to allow the loop to pass freely around the 15 bobbin-case, and the loop-taking point a is formed on the portion of the rim first referred to by cutting away a portion of the cup-like shell, one edge a² of the gap thus formed constituting the outwardly inclined 20 side of the hook point while the opposite edge a³ is substantially parallel thereto. This gap is much wider than the gap in the known hooks of similar construction and is bridged by a raised bridge piece C that 25 serves to control the loop. Within the hook body a seating D is formed for a peripheral rib e that is formed approximately centrally on the bobbin-case E and extends around approximately two thirds of its 30 periphery, and the bobbin-case is held up to the said seating when the machine is working partly by the pull on the bobbin thread and partly by the bobbin-case holding ring F hereinafter described.

35 The bobbin G is carried in the bobbin-case on a central pin or stud in substantially the usual manner.

The bobbin-case E is so constructed and arranged that the bobbin thread is drawn up in to the work from a point which is in the same vertical plane as the needle hole in the throat plate of the machine and situated outside the path of the hook point so that the bobbin thread does not require 40 to be deflected out of the path of the hook. The said point is a point e' situated on a projection or lug e² on the outer or closed end of the bobbin-case, which lug extends radially beyond the periphery of the case about centrally of that portion of same over 45 which the peripheral rib e does not extend. The bobbin thread is led from the bobbin through guide slot e³ and a guide channel e⁴ in the bobbin case to the lug e² and 50 drawn into an eye formed therein at the point e', and from the said eye it passes up between the outer face of the lug e² and a tension spring H to the needle hole in the throat plate. The inner face of the lug e² 55 assists in forming the loop to be engaged by the hook by preventing the formation of a loop at the opposite side of the needle to the hook.

The tension spring H is engaged in a 60 shallow vertical groove formed in the outer

face of the lug e² and is secured on the closed end of the bobbin case by a screw which is engaged in a threaded hole h in the end of the bobbin stud and which serves also for adjusting the tension on the bobbin thread. 70 The usual arrangement of the tension spring on the bobbin-case has the defect that it necessitates the employment of very small screws as they are engaged in holes in the thin shell of the bobbin-case. The arrangement for applying the tension to the bobbin thread has further advantages in that it permits the thread to be drawn off perfectly smoothly without any tendency to raise the spring from its seat, and that the tension can be readily adjusted while the bobbin-case is in position, without even turning back the ring holder. 75

The needle descends directly at the back of the lug e² into an aperture e⁵ formed 80 in the periphery of the bobbin case at that point. At the edge of the aperture e⁵, opposite to the lug e², an upstanding lip e⁶ is preferably formed, which lip assists in maintaining the bobbin case in its normal 85 position within the hook.

The tendency of the bobbin case E to rotate with the hook is counteracted by the shape of the contacting surfaces of the outer flange of the bobbin case and the ring holder F. The lug e² engages loosely in the vertical slot or groove, indicated in the drawing by the reference letter f, in the face of the ring, but the engagement must be such that the loop can readily pass between the lug 90 and the recess when being drawn up into the work rotation of the bobbin case being prevented by the formation of the aforesaid contacting surfaces. The ring holder F is preferably hingedly mounted so that it 95 can be readily turned back to allow the bobbin-case to be removed, and it is also preferably adjustable to permit of regulating its position relatively to the bobbin-case. The contacting surfaces of the bobbin-case and the ring holder are beveled and somewhat rounded to insure the ready passage of the loop but the rounded beveled portions gradually change in contour in the direction of rotation of the looptaker, and the ring 100 holder being correspondingly shaped the tendency of the case to rise when the bobbin thread is pulled and to rotate is counteracted. 105

What I claim and desire to secure by Letters Patent of the United States is:—

1. In a lock stitch sewing machine, the combination with a rotary hook, of a bobbin case within the same, a ring holder for said case, the said case and holder having corresponding contacting faces of gradually variable contour in the direction of rotation of the hook, said bobbin case having a needle aperture therein, a radial projection on the case directly in front of said aperture, said 110

projection having an eye therein through which the bobbin thread is led upwardly to the needle hole in the throat plate, the projection being so situated that the needle thread contacts with its inner face to help form the loop to be engaged by the rotary hook.

2. In a lock stitch sewing machine, the combination with a rotary hook, of a bobbin case within the same, a ring holder for said case, the said case and holder having corresponding contacting faces of gradually variable contour in the direction of rotation of the hook, said bobbin case having a needle aperture therein, a radial projection on the

case directly in front of said aperture, said projection having an eye therein through which the bobbin thread is led upwardly to the needle hole in the throat plate, the projection being so situated that the needle thread contacts with its inner face to help form the loop to be engaged by the rotary hook, and a tension spring on the outside of said projection adapted to bear on the bobbin thread as it passes upwardly over the outer side of said projection. 20 25

In testimony whereof, I herewith affix my signature.

CHARLES EDWARD FRANCIS.
